Patented Jan. 28, 1913.

UNITED STATES PATENT OFFICE.

JACK C. MORGAN, OF LOS ANGELES, CALIFORNIA, ASSIGNOR OF ONE-HALF TO ROBERT J. CONWAY, OF LOS ANGELES, CALIFORNIA.

SHAVING-BRUSH.

1,051,815.

Specification of Letters Patent. Patented Jan. 28, 1913.

Application filed September 24, 1912. Serial No. 722,103.

To all whom it may concern:

Be it known that I, JACK C. MORGAN, a citizen of the United States, residing at Los Angeles, in the county of Los Angeles and State of California, have invented new and useful Improvements in Shaving-Brushes, of which the following is a specification.

The invention relates to brushes and has for an object to provide a shaving brush for retaining the brush body of the shaving brush in spaced relation to the shelf or sill upon which the shaving brush is placed.

The invention embodies, among other features, a shaving brush having a weighted end in which the weight can be adjusted relatively to the brush so that when the shaving brush is placed upon a sill or shelf the brush body of the shaving brush will at all times be spaced from the sill or shelf and will not come in contact therewith, the shaving brush being adapted to lie in a plane perpendicular to the shelf or sill or at an acute angle thereto.

In the further disclosure of the invention reference is to be had to the accompanying drawings, constituting a part of this specification, in which similar characters of reference denote corresponding parts in all the views, and in which:

Figure 1 is a perspective view of the shaving brush showing the same in vertical position; Fig. 2 is a vertical sectional view of the brush, showing the same reposing upon a shelf and in an inclined position; Fig. 3 is a transverse sectional view taken on the line 3—3 in Fig. 2; Fig. 4 is a vertical sectional view of a modified form of brush showing the same in vertical position; and Fig. 5 is a similar view showing the modified form of the brush in an inclined position.

Referring more particularly to the views, I employ a shaving brush 10 including a handle 11 and a brush body 12, the brush body 12 preferably consisting of a series of bristles 13, the inner ends of which are seated and secured within the handle 11 in any suitable manner. The handle 11 terminates in a cylindrical reduced shank 14 threaded on the periphery thereof and provided at the lower end with a knob 15. A weight 16, preferably consisting of a collar 17 made of some heavy material, has threaded connection with the shank 14 and encircles the same, the said weight 16, in view of the threaded connection with the

shank 14, being adjustable thereon to be moved toward or from the lower end of the shank.

In the use of the device described, when the weight 16 is adjusted on the shank 14 so that the weight will be at the lower end of the shank 14, it will be readily seen that when the shaving brush 10 is placed upon a shelf or sill the knob 15 will support the shaving brush upon the shelf and the weight 16 will tend to hold the shaving brush so that the brush body thereof will be in spaced relation to the shelf. Now if the weight is moved upwardly a slight distance on the shank, and the shaving brush is placed upon a shelf or sill, the shaving brush will tend to tilt in view of the fact that the weight 16 is spaced a distance from the lower end of the shank. The shaving brush 10, however, will be prevented from tilting to a position that will cause the brush body 12 to contact with the shelf or sill in view of the provision of the collar 17, constituting the weight 16, and which, when the shaving brush tilts, will engage the shelf or sill, thus forming two points of contact to support the shaving brush in tilting position, as will be readily understood by referring to Fig. 2. If desirable, a pin 11^a can be placed upon the shank 14 to project therefrom, thus preventing the weight 16 from being entirely removed from the shank 14, the said pin being mounted on the shank a slight distance from the lower end thereof, as shown.

In Figs. 3 and 4 I disclose a modified form of brush and in which I employ a shaving brush 18 including a handle 19 and a brush body 20, the shaving brush 18 being similar to the shaving brush 10 but having the handle 19 thereof spherical in shape and hollow. A weight 21 is loosely mounted within the hollow portion of the handle 19 and the handle in the lower portion thereof is provided with an elongated slot 22, through which is passed a pin 23 having threaded connection with the weight 21, a head 24 of the pin 23 constituting a means for adjusting the weight 21 within the handle 19, as will be readily seen by referring to the views, it being understood that the head 24 is of a greater diameter than the width of the slot 22 so that when the pin 23 is tightened up on the handle 19, the weight 21 will be held rigidly within the handle and when the pin 23 is loosened relatively to the handle 19,

the weight can be adjusted to different positions within the handle and then secured in any of the desired positions by retightening the pin 23 on the handle 19, this being accomplished by simply screwing up on the pin 23 to engage the head 24 thereof with the periphery of the slot 22.

Thus with devices of the character described, the shaving brushes disclosed herein will be prevented from tilting on a shelf or sill so that the brush body 12 thereof will contact with the shelf or sill, it being well known that it is undesirable to have the brush body of a shaving brush engage any object, particularly when the brush body is covered with lather which is to be applied to the face and which should be kept clean.

and sanitary by preventing the brush body from coming in contact with another object when the shaving brush is not in use.

Having thus described my invention, I claim:

In combination with a shaving brush including a handle and a brush body, a weight mounted on the said handle and movable thereon to limit the tilting movement of the brush body when the handle is placed upon a shelf or sill.

In testimony whereof I affix my signature in presence of two witnesses.

JACK C. MORGAN.
